CLAIM

The ornamental design for a container handle, as shown and described.

DESCRIPTION

FIG. 1 is a top, front, right perspective view of a container handle in accordance with our design;

FIG. 2 is a bottom, front, right perspective view thereof;

FIG. 3 is a bottom, front, left perspective view thereof;

FIG. 4 is a front elevational view thereof;

FIG. 5 is a section view thereof taken along line 5-5 in FIG. 4;

FIG. 6 is an enlargement view of the container handle as shown in FIG. 5;

FIG. 7 is a section view thereof taken along line 7-7 in FIG. 4;

FIG. 8 is enlargement view of the container handle as shown in FIG. 7;

FIG. 9 is a section view thereof taken along line 9-9 in FIG. 4;

FIG. 10 is enlargement view of the container handle as shown in FIG. 9;

FIG. 11 is a section view thereof taken along line 11-11 in FIG. 6; and,

FIG. 12 is a section view thereof taken along line 12-12 in FIG. 6.

The dash-dash broken lines showing the container depict environmental subject matter that form no part of the claimed design. The dash-dot broken lines shown in FIGS. 5-10 depict boundary lines of an enlargement that form no part of the claimed design. The remaining dash-dot boundary lines depict claim boundary limits and form no part of the claimed design.

1 Claim, 11 Drawing Sheets
